REGLET AND COUNTER FLASHING

Abraham Herman, Los Angeles, Calif.

Application April 14, 1932, Serial No. 605,255

6 Claims. (Cl. 108—26)

My invention relates to a type of reglet and counter flashing which may readily be used on cement or brick walls and also for attachment to wood frame studding or the like, which is otherwise covered with stucco.

An object and feature of my invention is the construction of a reglet and a counter flashing with the counter flashing interconnected and attached to the reglet in such a manner that such counter flashing may be removed and then again replaced. The purpose of this removal is to allow recovering of a roof with roofing felt which includes the removal of the flashing on the wall, and then after the new roof and new 10 flashing is in place again attaching the old counter flashing to the reglet, which reglet has been left in position in a wall.

Another object and feature of my invention in one form is having the counter flashing with the upper part fitting underneath part of the reglet and having an upper and an outer part consisting of a flanged edge which may be crimped or bent into engagement with a flange on the reglet and thus securely attach the counter flashing to the reglet. In this form when it is desired to remove the counter flashing, the flanged edge is bent outwardly into disengagement with the flange of the reglet and the counter flashing bodily removed by slipping this downwardly between the wall and an outside vertical section of the reglet.

In another form of my invention, an object and feature thereof is forming the reglet with a relatively wide outstanding upper surface from a vertical section on the wall, providing this with a downturned flange, and interfitting and bolting the counter flashing to the angular bent portion of the reglet which extends beyond the wall. In this construction I provide the counter flashing with a main flashing section extending upwardly on the wall and with an outwardly bent top and downwardly extending flange. These are constructed to interfit with the flat top exposed surface of the reglet and the outer depending flange. Bolts may be either secured through the top exposed portion or the interfitting vertical flanges. In all forms of my invention the counter flashing is corrugated longitudinally to force the lower portion to have a tight contact with the 50 flashing on the wall.

My invention is illustrated in connection with the accompanying drawings, in which:

Fig. 1 is a section through a wall showing one form of my invention, this being a type for a concrete or brick wall.

Fig. 2 is a section of the reglet and forms showing the manner of installation on the reglet for the construction of Fig. 1.

Fig. 3 is a vertical section, being a modification of Fig. 1, in which the reglet is adapted for 60 attaching to studs over which there is a stucco coat subsequently put on.

Fig. 4 is a section of the reglet illustrating the manner of mounting on studs and the application 65 of the stucco wall surface.

Fig. 5 is a vertical section of a further modification adapted for concrete or brick walls and illustrating the reglet and counter flashing attached by bolts through a flange.

Fig. 6 is a section of the reglet of Fig. 5, indicating the forms used for securing the reglet and building the wall.

Fig. 7 is a vertical section somewhat similar to Fig. 5, in which the reglet and counter flashing 75 are bolted through sloping top surfaces.

Referring first to the construction of Fig. 1, this shows a reglet 11 which has a horizontal section 12 with an upturned flange 13, this being embedded in a wall 14 of concrete or brick. A depending vertical section 15 of the reglet is spaced 80 from and parallel to the wall surface, and this has a horizontal outstanding flange 16. The roof covering 17 has a flashing 18 extending upwardly on the face of the wall. Counter flashing 19 is provided with an upper portion 20 having a reverse bend at the top. These are flattened together, there being an inner section 21 and an outer section 22. An outstanding flange 23 extends from the section 22 and this flange has a bendable outer edge portion 24. This is bent 90 upwardly and crimped as indicated at 25 over the top of the outstanding flange 16. The double thick portion 20 fits snugly between the vertical section 15 of the reglet and the wall surface. The counter flashing has a corrugated skirt 26. This has a ridge 27, thus forming an outwardly sloping face 28 above the ridge and an inwardly sloping face 29 below the ridge. Adjacent the lower edge, a bent edge 30 contacts with the flashing on the wall and the lower edge portion 31 is flared 100 slightly outwardly.

In the construction of Fig. 3, a reglet 32 has a narrow horizontal section 33 and a vertical section 34, which vertical section is adapted to be nailed to studs 35 in the wall. This reglet has a downturned face portion 15 and a flange 16, as in Fig. 1. A stucco covering is indicated at 36 above and wood 37 below the reglet. This leaves a space between the vertical section 15 of the reglet and the face of the stucco wall and this portion. The 110

reverse bend section 20 of the counter flashing fits and is secured by the crimped section of the edge 24 of the flange of the counter flashing. The shape of the counter flashing and manner of attachment is the same as shown in Fig. 1.

In Fig. 2 I show a form which may be used in attaching the reglet of Fig. 1. This has formed boards 38 and 39 having the joint 40 in which fits the flange 16 of the reglet. This flange is caught by short nails 41 driven into the lower board. These boards are held in place in the usual manner for pouring concrete. By this construction the vertical section 15 of the reglet fits tightly against the concrete wall but may be pried outwardly for inserting the upper portion 20 of the counter flashing. If the wall is made of brick the reglet is inserted in the brick joints.

In Fig. 4 I illustrate the manner of attaching the reglet of Fig. 3. The wood panel 37 may be placed on the studs prior to fitting the reglet, which reglet is held secured to the studs 35 by nails 42.

In Figs. 5 and 7 I show a further modified form of my invention in which the counter flashing is bolted to the reglet. In this case the reglet 43 has a horizontal section 44 with a vertical flange 45, this being illustrated as having a reverse marginal bend 46, and is embedded in the wall, such being illustrated as of concrete or brick. There is a vertical section 47 and an outwardly and downwardly sloping section 48 with a vertically depending skirt 49.

In the construction of Fig. 5, this skirt has perforations 50. The counter flashing 51 has an upper strip 52 shaped to fit underneath the sloping section 48 of the reglet and has a downturned flange 53. The depending portion 54 on the inside is slightly corrugated with a ridge 55 and an outwardly flared lower edge 56, the edge 57 bearing against the roof flashing. When this counter flashing is fitted under the reglet, holes may be punched through the flange 53 of the counter flashing, and bolts 57' inserted through the perforations 50 and these punched holes. The bolts are illustrated as having heads with a screw driver kerf and nuts on the inside so that the counter flashing may be readily bolted to the reglet. The construction with the bolts on the vertical flange 49 is suitable for construction where the surface 50 of the building is covered with a stucco coat indicated at 58, this coat resting on the sloping surface 48 of the reglet.

In Fig. 7 I show another manner of attaching the counter flashing to the reglet suitable for a case in which the wall is not covered with stucco. In this case, the sloping surface 48 of the reglet and the sloping section 52 of the counter flashing are provided with perforations 59 through which extend the bolts 60.

A form suitable for holding this type of reglet prior to molding a concrete wall is illustrated in Fig. 6, in which a lower form board 61 and an upper form board 62 have beveled edges 63 at the joint 64, and through these beveled edges 65 extends the sloping section 48 of the reglet. The lower edge of the skirt 49 of the reglet is secured by nails 66 driven into the lower board 61. By

this construction the concrete may be poured and, after setting, the form is removed, leaving the reglet in position.

Various changes may be made in the details of construction without departing from the spirit or scope of the invention as defined by the appended claims.

I claim:

1. A building construction having a reglet with means for attachment to a building, such reglet having a depending vertical section spaced from the building wall and an outstanding horizontal flange, a counter flashing having a section to fit between the vertical section of the reglet and the wall, and having a flange fitting underneath the flange of the reglet with an outer edge with sections bent over the top of the flange of the reglet to detachably connect the counter flashing to such reglet. 85 90

2. A building construction having a reglet with means for securing same to a building wall, such reglet having a vertical depending section spaced from the wall, and a horizontal outstanding flange, a counter flashing having an upper edge with a reverse bend fitting between the vertical section 100 of the reglet and the wall, such flashing having a flange underneath the flange of the reglet, and an outer edge with sections bent over the top of the reglet flange to detachably connect the counter flashing to the reglet. 95 105

3. A building construction as claimed in claim 2, the counter flashing having upper and lower longitudinal corrugations with the edge of the lower corrugation engaging the flashing of the building, said corrugation being spaced from the 110 lower edge of the counter flashing.

4. A building construction as claimed in claim 2, the means for attaching the reglet to the building comprising a horizontal section connected to the vertical section, and a second vertical section 115 adapted for attachment to a wall, the horizontal section adapted to be embedded in a stucco wall covering.

5. A building construction having a reglet with means for attachment to a building, such reglet 120 having a depending vertical section spaced from the building and an outstanding horizontal flange, a counterflashing having a section to fit between the vertical section of the reglet and the wall, an outwardly and downwardly bent section fitting 125 behind the depending vertical section of the reglet, an outwardly extending portion of the counterflashing fitting underneath a flange of the reglet, the edge portion of the outwardly extending part of the counterflashing being bent over the top of 130 the flange of the reglet.

6. A building construction having a reglet with means for attachment to a building, said reglet having a depending portion spaced from the wall of the building and a horizontal flange, a counterflashing having one portion extending upwardly 135 back of the depending portion of the reglet and having a horizontal section fitting underneath the flange of the reglet, and an edge portion bent over the top of the reglet flange. 140

A. HERMAN.
